HUMPHREY THOMAS LOGAN, OF LONDON, ENGLAND.

MACHINE-GUN AND THE LIKE.

1,318,214.

Specification of Letters Patent.

Patented Oct. 7, 1919.

Application filed July 20, 1917. Serial No. 181,930.

To all whom it may concern:

Be it known that I, HUMPHREY THOMAS LOGAN, a subject of the King of England, of 3 Ravencourt Square, Hammersmith, London, W., England, at present with the British Expeditionary Force, France, have invented certain new and useful Improvements in Machine-Guns and the like, of which the following is a specification.

10 This invention is for improvements in or relating to machine-guns and the like, and has for its object to provide means whereby the rate of automatic firing can be reduced or varied from the maximum downward to 15 any desired extent while yet maintaining the automatic action.

The invention relates to machine-guns of the type having a member which is reciprocated automatically and effects the ignition 20 of a cartridge when driven forward by a spring, or sets the parts ready for the release of the firing-bolt, the said spring having been loaded by the previous rearward movement of the reciprocating member. This member is variously termed the breech-block, firing-bolt, piston-rod, according 25 to the type of gun in which it is found, and has a rectilinear movement, being driven forward for firing or preparatory 30 to firing by its spring and rearward to load the spring by the recoil resulting from the explosion of the charge. In the .303 Lewis machine-gun, this member is known as the "piston-rod," and this term will be used 35 throughout this specification and claims for the reciprocating-member as the invention will be described with reference to the said Lewis gun, but it will be understood that the term includes any similar reciprocating 40 member in other makes of guns and the invention is not restricted to the Lewis gun.

It has previously been proposed to employ a dashpot device for slowing the rate of firing and this device comprised a spring-controlled member which was pushed back 45 against its spring by the return movement of the breech-block which takes place after one shot has been fired prior to the next being fired. After the set-back of the dashpot member for the breech-block the final 50 movement of the latter left the dashpot member free so that it could advance and strike the same for the next release for firing; the length of the period between the 55 return of the breech-block and the next op-

eration for firing thus depended upon the degree of leakage allowed the dashpot mechanism. The hand-trigger or its equivalent also controlled mechanism for effecting the operation of the sear automatically without waiting for the movements of the dashpot member when full-speed firing was required. The dashpot mechanism could only be operated at one speed unless an adjusting-screw controlling the leakage was operated 60 to effect a re-adjustment of the rate of firing, which screw was not accessible without stopping the action of the gun.

According to the present invention, a machine-gun of the type described and having a dashpot mechanism for retarding the firing movement of the piston has combined with the hand-trigger a release-valve for the dashpot and operative connecting means between this and the trigger so that as the 70 latter is moved farther back the valve is increasingly opened and the rate of firing thereby accelerated.

According to another feature of this invention a machine-gun of the type described 80 having a dashpot device for retarding the rate of firing has combined with the "piston-rod" means for automatically locking the latter back against forward movement for firing when the hand-trigger is still in the 85 firing position and means operatively connecting the dashpot with the aforesaid automatic locking means to release the same by the return movement of the dashpot.

Preferably the operative connection between the hand-trigger and the release-valve for the dashpot takes the form of a sear which holds the "piston-rod" against 90 firing movement but is interconnected with the hand-trigger so that when the latter is moved to the firing position it releases the "piston-rod" and when the hand-trigger is still further moved back the sear is brought 95 into contact with and commences to open the release-valve.

The accompanying drawing, which is entirely diagrammatic, illustrates that part of a Lewis gun to which the present invention applies.

The piston-rod A is normally locked back 105 against its controlling spring by a sear B which is pivoted at B¹ and is connected at B² to the trigger C. The spring for driving the piston-rod forward for firing is not shown, but it operates to drive this forward 110

in the direction indicated by the arrow and is loaded by the recoil movement of the piston-rod which is in the reverse direction to that indicated by the arrow.

5 For the purpose of this invention, a second sear D is provided which may also be pivoted at B¹ and has a downwardly-directed tail-piece D¹. Both sears are normally kept in engaging position by one or 10 more springs E so that when they are left free, they snap into the recess A² provided for them in the piston-rod A.

Mounted beneath the sears is a dashpot F in which slides a dashpot-member F¹, the 15 said member being in the form of a hollow piston driven outward by a spring F². Behind the piston is a spring-controlled valve G of the needle type, which, when depressed against the action of its spring, admits air 20 to the dashpot, and a non-return valve G¹ is provided whereby air can be expelled from the dashpot.

The dashpot-member F¹ has at its forward end a projection F³ which lies in the path of 25 the tail-end D¹ of the sear D. A lever H is pivoted at H¹ and has pivotal connection at H² with the forward-end of the dashpot-member. At the upper end of the lever H, a well-known one-way trip device H³ is 30 mounted, and coöperating with this is a catch A³ on the piston-rod A.

The operation of this mechanism is as follows:—

When the trigger C is pulled back in the 35 direction of the arrow for firing, the sear B is first released and this, if no second sear were provided, would start the gun firing at full speed. At the time of starting, the second sear is held back by the dashpot member so that one shot is fired directly the 40 first sear C is released by the hand-trigger. On the recoil of the piston-rod the second sear D drops into the notch A² and remains there until the dashpot-member F² has moved 45 out on its return movement so that its forward end comes into contact with the tail-end D¹ of the sear, and this withdraws the sear. The piston-rod then advances and fires the next cartridge. In this advance, the 50 catch A³ passes the lever H, which will be in the position indicated by dotted lines, by swinging over the trip, also indicated by dotted lines. The recoil then returns the piston-rod and in so doing the catch A³ engages the end of the lever H and brings it back to the position shown in full lines so that the dashpot-member is thrust into the dashpot against the action of the spring F² which is thereby loaded and the surplus 55 air from the dashpot is expelled through the valve G¹. The lever H in swinging over is brought out of the path of the catch A³ so that the catch can pass on to the position shown in full lines, in which position 60 the piston-rod is fully returned. Directly

the return has taken place, the dashpot member F¹ begins to advance under the action of its spring F² and no further shot will be fired until this has again released the second sear D, although the first sear 70 B is still being held back by the trigger C. The dashpot thus constitutes a timing-device and is adjustable in that the length of the intervals allowed between the shots fired can be controlled by increasing or decreasing the rate at which the dashpot is allowed to be filled with air. If the valve G is not opened at all, the mechanism will operate at its slowest, as the advance of the dashpot-member F¹ can then only take place at the 80 rate at which the dashpot can fill with air through leakage, but if the trigger C is pulled back farther, the sear B is brought down upon the top of the valve G and displaces it against the action of its spring. 85 In the drawing, the sear is shown as resting upon the top of the valve but not yet depressing the same. It will be appreciated, therefore, that the farther the trigger C is pulled back, the greater will be the freedom 90 with which the dashpot is filled with air and thus its speed of operating will increase and so the rate of firing can be increased.

To enable the firing to take place at full speed, the timing-device can be cut out entirely. This is done by a depending lug 95 D² on the sear D which carries a pin D³. This pin projects laterally beneath the sear B so that when the trigger C is pulled right back, the sear B will engage this pin and hold the sear D free of the notch A² in the piston-rod.

From the above it will be seen that a large range of adjustability is permitted so that the gun might be made to fire at any rate 105 desired, say, from one shot in one or more minutes up to the full speed, but in some cases it might be preferred to provide the gun with only two speeds, that is, one in which the dashpot is operative with a given 110 size of air-admission orifice and the other in which the dashpot is cut out so that the gun works at full-speed; such an arrangement it will be understood is covered by the term "adjustable" timing-device, although the timing-device itself in such case is only operative at one speed and cut out for the other.

What I claim as my invention and desire to secure by Letters Patent is:—

1. In a machine gun, the combination with the piston rod, the trigger, and an adjustable timing device for retarding the firing movement of the piston rod, said timing device comprising a spring-pressed driving member, a regulating member for controlling the latter, and means adapted to be driven by the recoiling piston rod for driving the said driving member against the action of its spring, of means operatively connecting the 120

trigger with said regulating member so that the timing device is controlled by moving the trigger.

2. In a machine gun, the combination with the piston rod and a dashpot device comprising a plunger, for retarding the rate of firing, of locking means for automatically locking the piston rod back against forward movement for firing when the trigger is still in the firing position, the said plunger being adapted to release the said locking means during its return movement.

3. In a machine gun, the combination with the piston rod, and the trigger, of locking means operatively connected with the trigger for automatically locking the piston rod in its rear position when the trigger is in its normal position and for releasing the same when the trigger is in its firing position, a valve-controlled timing device for retarding the rate of firing controlled by said locking means, and a locking device adapted to be actuated by said timing device for automatically alternately locking the piston rod in its rear position and releasing the same for firing while the trigger is still in its firing position.

4. In a machine gun, the combination with the piston rod and the trigger, of a sear operatively connected with the trigger for automatically locking the piston rod in its rear position when the trigger is in its normal position and for releasing the same when the trigger is in its firing position, a valve-controlled timing device for retarding the rate of firing controlled by said sear, and a second sear adapted to be actuated by said timing device for automatically alternately locking the piston rod in its rear position and releasing the same for firing while the trigger is still in its firing position.

5. In a machine gun, the combination with the piston rod and the trigger, of a sear operatively connected with the trigger and adapted to be rocked thereby into an end locking position for locking the piston rod in its rear position when the trigger is in its normal position, and into an end withdrawn position after releasing the piston rod when the trigger is in its firing position, a valve-controlled timing device for retarding the rate of firing controlled by said sear, and a second sear adapted to be actuated by said timing device after the release of the piston rod by the former sear for automatically alternately locking the piston rod in its rear position and releasing the same for firing while the trigger is still in its firing position, the former sear being adapt-

ed to coact with and arrest the second sear in its releasing position when the former sear is rocked into its end withdrawn position.

6. In a machine gun, the combination with the piston rod and the trigger, of a spring-influenced sear operatively connected with the trigger and adapted to be rocked thereby into an end locking position for locking the piston rod in its rear position when the trigger is in its normal position, and into an end withdrawn position after releasing the piston rod when the trigger is in its firing position; a valve-controlled timing device for retarding the rate of firing controlled by said sear, and a second spring-influenced sear having a tail piece adapted to be actuated by said timing device after the release with the piston rod by the former sear for automatically alternately locking the piston rod in its rear position and releasing the same for firing while the trigger is still in its firing position, and a projecting member carried by the second sear and adapted to be held by the former sear and thereby prevent the tail piece being actuated by the timing device.

7. In a machine gun, the combination with the piston rod and the trigger, of an adjustable timing device comprising a valve-controlled dashpot for retarding the firing movement of the piston rod, and a sear having one end operatively connected with the trigger, and its other end adapted to lock the piston rod in its rear position when the trigger is in its normal position and to operate the valve of the timing device after the piston rod has been released and the trigger has been moved into its firing position.

8. In a machine gun, the combination of a piston rod, a trigger, a spring-pressed sear having one end operatively connected to the trigger and its other end normally locking the piston rod in its rear position, an adjustable timing device comprising a dashpot having an air port, a valve controlling the air port adapted to be operated by the sear, a spring-pressed plunger movable in the dashpot, a lever pivotally connected to the plunger and a trip device carried by the plunger and adapted to be driven by the piston rod during its recoil, and a second spring pressed sear having one end normally locking the piston rod in its rear position and having on its other end a tail piece adapted to be actuated by the plunger for releasing the piston rod.

In testimony whereof I have signed my name to this specification.

HUMPHREY THOMAS LOGAN.
